AMMUNITION

Raymond S. Holmes, Alton, Ill., assignor to Olin
Industries, Inc., East Alton, Ill., a corporation
of Delaware

Application September 29, 1947, Serial No. 776,837

12 Claims. (Cl. 102—42)

1

This invention relates generally to shot cartridges and particularly to shot cartridges of the type in which there is a positive seal between the combustion gases and the shot charge. This application is a continuation-in-part of my prior copending application, Serial No. 616,526, filed September 15, 1945.

Numerous workers in the prior art have believed that the performance of shot shells would be improved by the provision of wadding of such character that a substantially hermetic seal would exist between the shot charge and the propellant charge thus to positively confine the powder gases behind the shot charge, both in the shell itself and in the gun barrel, and many proposals in this direction have been made. Experience demonstrated, however, that the rounds provided with the supposedly improved seal behaved in an undesirable manner, yielding patterns which were erratic and less suitable than the products which they were intended to supersede.

These experiences with substantially hermetic wadding led to the belief that some leakage of powder gas past the wadding was not only desirable but necessary to secure uniformity of patterns from round to round and satisfactory distribution of pellets in the pattern of the individual rounds. In my copending application, Serial No. 616,526, I pointed out that such gas leakage was not necessary in the case of shot shells which were free of top (over-shot) wads. In fact, test data included in said application show that, absent an end closure of such character as to obstruct the movement of the shot pellets through space, an hermetically sealing gun wad (between the propellant charge and the shot charge) does, in fact (contrary to previous experience), result in improved patterns and other desirable features. Subsequent observations not only confirm the aforesaid discovery, but extend it beyond shells with integral top closures (as shown in said application) to shells whose ends are closed by means of wads which offer no substantial retardation to the travel of the shot pellets through space.

While it has heretofore been proposed, as in United States Patent No. 929,866, to eliminate the top wad and close the end of the shot shell tube by deformation and infolding of the side walls of the tube, and indeed substantial quantities of shot shells have been manufactured with the ends so closed, the lesson learned by the art with respect to the necessity of gas leakage has continued to prevail so that those shells whose end closures have been integral with the

2

side walls of the tube have heretofore been provided with wadding between the shot charge and the propellant charge, which admitted of some gas leakage.

5 It is evident, of course, that such gas leakage represents a loss of propellant power and that the heat of the combustion gases in contact with the shot charge contributes to the tendency of the shot pellets to weld together, as well as to their tendency to foul the gun bore.

In the aforesaid application, the substantially hermetic wadding between the propellant and the shot consisted of a flanged disc wherein the flanges were smooth and extended in the direction of the propellant, snugly engaging the interior of the shell tube. While such wads were eminently satisfactory from the performance standpoint, some difficulty was encountered in loading such shells by automatic machinery in that the wad was driven home so rapidly as to build up substantial air pressures behind it. In some cases (which were rare but nonetheless too prevalent for the highest quality ammunition), the pressure of the thus entrapped air reached 20 a magnitude sufficient to displace—cock—the wad when the mechanical force thereon was released. Quite naturally, the ballistic results obtainable from such a shell were at variance with the desiderata.

The object of the invention, generally stated, 30 is to provide a shot shell in which leakage of gas past the wadding is minimized without the disadvantageous effects above described.

Another object of the invention is to provide a shot cartridge of the type described, in which 35 is incorporated a gun wad of such form and dimensions as to furnish an optimum gas seal with the gun barrel without adversely affecting the pattern.

Another object is to provide a gun wad which 40 will furnish an effective gas seal and also be capable of withstanding the firing pressure without disintegrating.

Further objects will appear from the detail description taken in connection with the accompanying drawings, in which:

Figure 1 is a longitudinal sectional view of a shot cartridge embodying the invention;

Figure 2 is a perspective view of a gun wad usable in the shell shown in Figure 1;

50 Figure 3 is a view corresponding to Figure 2, but showing another form of gun wad wherein the flanges are fluted;

Figure 4 is a sectional view of another embodiment of a shot cartridge embodying the present invention; and

Figure 5 is a perspective view of a breakable wad utilized in effecting the end closure of the shell shown in Figure 1.

According to the present invention, a shot shell, provided with a substantially self-sealing wad between the shot charge and the propellant charge, has its end closed to confine the charges by an evanescent closure. By evanescent closure, as used herein, is meant a closure which will confine the shot within the shell during ordinary handling, but which, when the shell is fired, has the capacity of substantially freeing itself from the trajectory of the shot pellets, so that there are no solid parts of a character such as to obstruct the movement of the shot pellets through space. Such escape from the trajectory may be either real (as in the case of tube-integral closures) or effective (as in the case of disintegrating top wads) provided that, at and beyond the muzzle of the gun, the end closure does not exist in a form which will deflect or impede the travel of the shot pellets through space. Accordingly, such an evanescent closure may, for example, be of the form disclosed generally by United States Patent No. 929,866 wherein the end of the tube is creased and infolded to form the closure and, upon firing, such end closure remains integral with the shell. Alternatively, the evanescent closure may involve the use of so-called frangible, breakable, or disintegrating wad material, either of the character heretofore known in the art or of the particular character hereinafter described in more detail.

Since the present invention contemplates the disposition of a substantially self-sealing wadding between the propellant charge and the shot charge of a shot shell, such wadding will hereinafter be referred to as a "gun wad" in order to definitely distinguish the same from the top wad commonly employed to close the end of shot shells.

The present invention particularly contemplates the combination of an evanescent closure for the shot shell tube with a self-sealing gun wad of the character of a flanged disc arranged with the flanges to trail the web of the wad upon firing, i. e., with the flanges directed toward the base of the loaded shell. Such a flanged disc may be formed of consolidated fibrous sheet material, such as paper. Shells embodying self-sealing gun wads of this type with a shot shell tube having an evanescent closure not only exhibit uniformity of pattern and elimination of lead deposit in the gun bore, but also exhibit a unique uniformity of report, marked reduction in "confettiing," and considerable reduction of powder residue in the gun barrel.

The present invention further contemplates the provision in the flanges of the gun wad aforesaid of a succession of axially extending flutes. These may be formed concurrently with the flanging of the disc by the utilization of fluted male and female forming dies.

Referring now to Figure 1 of the drawings for an illustrative embodiment of the invention, the shell consists of a suitable base 1 and the usual paper tube 2. A primer assembly 3 is mounted in the base 1, and thereabove within the tube 2 is a propellant charge 4.

In the embodiment shown in Figure 1, a gun wad 5 of the character shown in detail in Figure 2 is provided immediately overlying the propellant 4, and confining the latter. The gun wad 5 consists of a flanged disc of consolidated fibrous sheet material such as paper. Alterna-

tively, the gun wad may take the form shown in Figure 3 wherein the flanged disc 15 shown is provided with a succession of axially-extending flutes 6 in the flanged portion, but is otherwise identical with that shown in Figure 2. As hereinabove indicated, the flutes 6 may be formed concurrently with the flanging of a flat disc of paper, by forcing the disc through male and female dies, one or both of which are provided with axially-extending grooves. For optimum sealing, it has been found that the depth of the flange should be about one-tenth of the diameter of the completed wad. When the depth of the flange is appreciably less than the lower limit mentioned, for example 6% of the diameter, an efficient gas seal is not obtainable. Increasing the depth of the flange beyond about one-third the diameter increases the manufacturing difficulties, without contributing any advantageous results. Excellent gun wads for use in 12-gauge shot cartridges have been obtained by flanging circular discs of paper 0.035" in thickness, ranging from 0.875" to 1.20" in diameter, using a cupping die having a male member (defining the interior diameter, between the flanges of the wad), 0.720" in diameter.

It has further been found that gun wads which are not subject to undesirable disintegration and delamination when fired in a gun are obtainable by the use of heavily calendered paperboard. Impregnation of the cardboard with a high melting point wax composition is desirable, though not essential. While a variety of wax compositions, having melting point higher than about 50° C., has been found effective for the purpose, without adversely affecting the propellant powder charge, particularly good results have been obtained with the use of microcrystalline waxes of petroleum origin, such as "Socony 2300" and "Moore and Munger 3300". For example, wads of cardboard were thoroughly impregnated with about 25% of their weight of wax by ten minutes' submersion in molten wax at 100° C. followed by ten minutes of centrifuging at 30° C.

In the embodiment shown, a succession of filler wads, including a card wad 7 and two molded wads 8 of conventional form, are inserted above the gun wad 5. Therebeyond, the shot charge 9 is placed in the tube 2, and finally the end of the tube 2 is closed to confine the shot charge, the wadding, and propellant, by the provision in the illustrated embodiment of a disintegrating top wad 10, held in place by inturning and crimping the end of tube 2, as shown at 11.

While the wad 10 may be formed of any suitable composition known in the art for the production of a frangible, disintegrating, or breakable top wad, good results have been achieved with wads which are cut from any of a great variety of chipboard, about 0.025" thick. After cutting the discs from the paperboard sheets, the discs are immersed in a sodium silicate solution having a specific gravity of 1.1 for approximately thirty minutes. Thereafter the discs are removed and drained of excess sodium silicate solution. The discs are then dried with circulating hot air at a temperature of 125° C. for two hours. During the drying cycle, the discs are continuously tumbled to prevent sticking together. Thereafter the discs are aged for a period of about two days, to allow the sodium silicate to fully set before the wads are applied to shot shell tubes.

Another embodiment is shown in Figure 4, wherein the components are identical with those

shown in Figure 1, save that in the embodiment of Figure 4, the evanescent closure is accomplished by creasing the tube 2 near its mouth at, for example, six equidistant places, and then infolding the creased portion to provide a closure 12 integral with the tube 2, in the manner generally comparable to that disclosed in United States Patent No. 929,866. The tube-integral closure utilized in this embodiment results in a somewhat shorter shell than that shown in Figure 1, when tubes of the same original length are utilized. In order to accommodate the same propellant and shot charges in the two shells, however, the difference in dimension is made up by changing the thickness of the wadding which separates the propellant from the shot charge. Consequently, in the embodiment shown in Figure 4, the filler wads 8 of the previous embodiment are replaced by a single filler wad 18 of the same type, but of larger axial dimension than the combined axial dimension of the two filler wads 8 in the previous embodiment.

Comparative tests among a series of shells, with and without self-sealing gun wads of the character above described, and with and without the evanescent end closure of the shot shell tube, demonstrate the great superiority patternwise of the self-sealing gun wad with evanescent end closure. For example, nine 12-gauge game-load series of forty rounds each were fired, with the following pattern results:

Series	Top Closure	Over Powder Wad	Pattern—Percentage of Pellets in 30" Circle at 40 Yards		
			Average, 40 Rounds	Max.	Min.
1.	Fig. 1	Conventional	68	74	60
2.	Fig. 4	do	64	74	54
3.	Conventional	do	63	73	53
4.	Fig. 1	Fig. 2	74	82	67
5.	Fig. 4	do	74	81	63
6.	Conventional	do	61	80	43
7.	Fig. 1	Fig. 3	75	85	62
8.	Fig. 4	do	75	86	66
9.	Conventional	do	63	79	41

In another test, using 12-gauge traploads, an additional nine-series of forty rounds each were fired, with the following pattern results:

Series	Top Closure	Over-Powder Wad	Pattern—Percentage of Pellets in 30" Circle at 40 Yards		
			Average, 40 Rounds	Max.	Min.
10.	Fig. 1	Conventional	62	74	50
11.	Fig. 4	do	60	76	48
12.	Conventional	do	58	73	41
13.	Fig. 1	Fig. 2	68	74	55
14.	Fig. 4	do	69	76	59
15.	Conventional	do	59	72	43
16.	Fig. 1	Fig. 3	70	76	63
17.	Fig. 4	do	68	73	59
18.	Conventional	do	59	72	41

The "conventional" over-powder wadding in series 1, 3, 10, and 12, and series 2 and 11, were identical with that shown in Figure 1 and Figure 4, respectively, save that the gun wad 5 or 15 was replaced by a duplicate of the card wad 7. The "conventional" top closure in series 3, 6, 9, 12, 15, and 18 was identical with that shown in Figure 1, save that the breakable top wad 10 was replaced by a card wad of the same size and shape. All other components of the shells involved in the several series of game-load tests were identical.

Likewise, all other components of the shells involved in the several series of trapload tests were identical. The trapload differed from the game-load in propellant charge, shot charge, and base structure (the latter being as specifically shown in the parent application Serial No. 616,526) in the usual manner.

From the foregoing test results, it is apparent that with a conventional end closure, the use of either style (Figure 2 or Figure 3) of self-sealing gun wad was productive of pattern results in some cases worse, and in no case substantially better, than with conventional over-powder wadding. On the contrary, with the evanescent end closures (of either the Figure 1 or Figure 4 type) the average patterns are considerably better with the self-sealing gun wad than with the conventional over-powder wadding. While the breakable top wad type of end closure appeared in all combinations to yield patterns somewhat better than the conventional top closure, the improvement was particularly striking in the combination with the self-sealing gun wad (of either style). In the latter case, while the average pattern is only one or two percentage points better when, with conventional over-powder wadding, the tube-integral end closure, rather than the conventional end closure, is employed (compare series 2 vs. 3, 11, vs. 12); where the self-sealing gun wad is used, the difference becomes thirteen (series 5 vs. 6), twelve (series 8 vs. 9), ten (series 14 vs. 15), and nine (series 17 vs. 18) percentage points. Moreover, the patterns resulting from shells where in either the over-powder wadding or the end closure was conventional, were consistently more erratic (see minimum column) than those resulting from shells having either type of evanescent closure, with either type of cupped wad. This clearly demonstrates a peculiar cooperative action between the cupped over-powder wad and the evanescent end closure.

Additionally, the tested shells which were provided with both an evanescent end closure and the cupped gun wad were characterized by a greater uniformity of report than the tested shells which omitted either or both of these features. These improvements in pattern and report are accomplished without sacrifice of muzzle velocity or velocity over a range of forty yards. Indeed, in most instances the muzzle velocity and the average velocity over forty yards was increased above the values obtainable where the same propellant and shot charges were used with conventional components.

From the foregoing description, it is apparent that the invention accomplishes its objects, and provides a substantially improved shot shell. While the invention is not limited to shot shells provided with components as specifically shown in the drawings, it is evident that the improved results are accomplished by the combination of an evanescent top closure and a self-sealing gun wad. The other components of the shell may be varied at will to fit the conditions for which the load is intended, in accordance with the usual practice in the ammunition art, and without departing from the spirit of the invention or the scope of the appended claims.

Having thus described the invention, what is claimed as new and desired to be secured by Letters Patent is:

1. A shot shell having a tube, a propellant charge and a loose shot charge within the tube, 75 a flanged disc wad between the propellant charge

and the shot charge, and an evanescent closure for the tube contiguous with the shot charge.

2. A shot shell having a tube, a propellant charge and a shot charge within the tube, a flanged disc wad between the propellant charge and the shot charge, and an evanescent closure for the tube comprising a frangible wad.

3. A shot cartridge having a shell, a charge of propellant powder therein, a gun wad consisting of a flanged disc of consolidated fibrous material pressed into contact with and enclosing the upper portion of the said powder charge, a loose shot charge above the said wad, and an evanescent closure for the shell contiguous with the shot charge.

4. A shot cartridge having a shell, a charge of propellant powder therein, a gun wad consisting of a flanged disc of consolidated fibrous material pressed into contact with and enclosing the upper portion of the said powder charge, a shot charge above the said wad, and an evanescent closure for the shell comprising a frangible wad.

5. A shot cartridge having a shell, a charge of propellant powder therein, a gun wad consisting of a flanged disc of fibrous material pressed into contact with and enclosing the upper portion of the said powder charge, said wad being impregnated with a high melting point wax, a shot charge above the said wad, and an evanescent closure for the shell comprising a frangible wad.

6. A shot cartridge having a shell, a charge of propellant powder therein, a gun wad consisting of a flanged disc of fibrous material pressed into contact with and enclosing the upper portion of the said powder charge, said wad being impregnated with a microcrystalline wax, a shot charge above the said wad, and an evanescent closure for the shell contiguous with the shot charge.

7. A shot cartridge having a shell, a charge of propellant powder therein, a gun wad consisting of a flanged disc enclosing the upper portion of the said powder charge, the length of the flanges of the disc being substantially one-tenth to one-third the diameter of the disc, a loose shot charge above the said wad, and an evanescent closure for the shell contiguous with the shot charge.

8. A shot cartridge having a shell, a charge of propellant powder therein, a gun wad consisting of a flanged disc pressed into contact with and enclosing the upper portion of the said powder charge, the depth of the said flanged disc being

substantially one-tenth its diameter, a loose shot charge above the said wad, and an evanescent closure for the shell contiguous with the shot charge.

9. A shot cartridge having a shell, a charge of propellant powder therein, a gun wad consisting of a flanged disc pressed into contact with and enclosing the upper portion of the said powder charge, at least one resilient wad and a loose shot charge superposed on the said flanged disc, and an evanescent closure for the shell contiguous with the shot charge.

10. A shot cartridge having a shell, a charge of propellant powder therein, a gun wad consisting of a flanged disc of pressure-resistant material over the said powder charge, a loose shot charge above the said wad, and an evanescent closure for the shell contiguous with the shot charge.

11. A shot shell having a tube, a propellant charge and a loose shot charge within the tube, a flanged disc wad between the propellant charge and the shot charge, said wad being pressed into contact with the propellant charge to confine the same, and an evanescent closure for the tube contiguous with the shot charge.

12. A shot shell having a tube, a propellant charge and a loose shot charge within the tube, a substantially self-sealing gun wad between the propellant charge and the shot charge, and an evanescent closure for the tube contiguous with the shot charge.
